United States Patent

Des. 235,274
Patented June 3, 1975

235,274

OPHTHALMIC STAND

John T. Armbruster, Niagara Falls, N.Y., assignor to
American Optical Corporation, Southbridge, Mass.

Filed Feb. 23, 1973, Ser. No. 335,188

Term of patent 14 years

Int. Cl. D24—01

U.S. Cl. D57—1 E

FIG. 1

FIG. 2

FIG. 3

FIG. 4

FIG. 5

FIG. 1 is a side elevation of an ophthalmic stand showing my new design;

FIG. 2 is a fragmentary side view of the upper carriage member;

FIG. 3 is a fragmentary side view of the lower carriage member;

FIG. 4 is an elevated front perspective view of the ophthalmic stand; and

FIG. 5 is a lower rear perspective view from a position substantially opposite that of FIG. 4.

I claim:

The ornamental design for an ophthalmic stand, as shown and described.
